BOX OF FOLDABLE SHEET MATERIAL

Cecil T. Jones, Modesto, Calif., assignor to Container Corporation of America, Chicago, Ill., a corporation of Delaware

Application April 29, 1955, Serial No. 504,749

2 Claims. (Cl. 229—34)

This invention relates to foldable paper boxes, and more particularly to such boxes which may be formed by folding panels from an integral substantially rectangular blank with a minimum waste of material, and which provides strong reinforcement where needed, and which, when folded, locks itself in box form by interfit of its parts without the necessity for gluing or stapling.

While the preferred material is sheet corrugated paper board, any other suitable type of foldable sheet material may likewise be employed.

Briefly described, the invention comprises a substantially rectangular integral foldable paper blank having slits and scored fold lines forming panels which, when folded, provide a box having walls at sides and ends, a bottom and a two-flap closure top, the top flaps being preferably scored or perforated for severance removal, and the walls providing a plurality of overlying panels for structural strength, the panels in the end walls preferably being relatively spaced, providing an air space for insulation, refrigeration or ventilation, said spaced end walls preferably having an opening therein for a hand grip, and the panels interfitting relatively whereby the box may be readily folded, and the panels locked upon themselves in such form or folded position into a rigid box structure of great strength.

One object of the invention is to provide a foldable box from a single integral blank which, when folded, is self-locking, strongly reinforced in its vertical dimensions to carry a relatively heavy superimposed load when stacked, and highly resistant to rough handling in shipment.

Another object is to provide a reinforced foldable paper box with readily removable cover panels, and which has insulating space and ventilating vents within its walls, and with hand grip openings for ease of handling.

The foregoing and other objects of the invention will be apparent from the specifications of one form of the invention which is described herein and illustrated in the accompanying drawings to which reference is made.

In the drawing:

Fig. 1 is a plan view of a blank from which the box of the invention is formed.

Fig. 2 is a perspective view of the box panels in partly folded position.

Fig. 3 is a perspective view of the box panels in a further folded position, as compared to Fig. 2, two panels being shown fragmentarily.

Fig. 4 is a perspective of the completely folded box with cover panels closed.

Fig. 5 is a perspective of the completely folded box with cover panels open and showing the interior.

Fig. 6 is a longitudinal vertical section on line 6—6 of Fig. 7.

Fig. 7 is a transverse vertical section on line 7—7 of Fig. 6.

Referring to the drawings in which like reference characters indicate corresponding parts in the several views,

2

and referring firstly to Fig. 1, the reference character 21 indicates generally an integral blank of foldable sheet material, such as corrugated paper board or the like, which, it will be noted, is generally rectangular in plan without substantial loss of material in forming its several panels. The blank is divided into panels by appropriate slits and score lines for bending upon itself into box-forming relation, the slits separating panels being shown in full line and the scored fold lines being shown in broken lines.

Centrally of the blank is a rectangular bottom panel 22 having slots 23 therethrough adjacently spaced from opposite edges, which in the folded box are the end edges. Arranged around the four perimeter edges of the rectangular bottom panel are four sections of panels, *a*, *b*, *c*, and *d*, which are separated relatively by slits *e*, the panel sections being integral with the bottom panel at the four scored fold lines 25*a*, 35*a*, 45*a* and 50*a*. Each section is divided into several relatively foldable rectangular panels which provide respective sidewalls, end walls and top for the box.

The number and purpose of the several panels in the sections *a* and *b* are similar, though the arrangement of the panels therein is varied; and likewise, the number and purpose of the several panels in the sections *c* and *d* are similar, though the arrangement thereof is varied. At this point of description these composite panel sections cannot be referred to in the usual conventional manner of side sections and end sections, because each of the sections *a*, *b*, *c* and *d* include both side and end panels in the completed folded box, and the top panels are also included in the sections *a* and *b*.

Having noted the foregoing observations of the sections, the sections *a* and *b* each comprise opposite sidewall panels 25 and 35 each of which has one longitudinal edge adjoining the bottom panel at score lines 25*a* and 35*a*, the opposite edge of each of said sidewall panels 25, 35 having integrally and foldably connected to its opposite longitudinal edge a top closure flap panel 26 and 36, at foldable score lines 26*a* and 36*a*. At the opposite ends of each top closure panel there is a slit *f* which maintains the said closure panels free for folding. Adjacent from the score lines 26*a* and 36*a* the sidewall panels 25 and 35 each has a weakened tear line 27 and 37 which are parallel to and adjacently spaced from the score lines 26*a* and 36*a*. The tear lines may be heavily scored or finely perforated, or substituted by a tearable strip of adhesive tape to permit tearing of the top closure panels from the box for display purposes when the box is opened. The side wall panels 25, 35 each has connected at its opposite ends, as by the respective scored fold lines 29*a*, 32*a*, and 39*a*, 44*a*, certain end panel sections which are referred to as supplemental end panels, since they fold within the other end panels in the completely formed box.

Since the sections *a* and *b* are similar except for the diagonal transposition of similar panels in the blank (such as relatively diagonal panels 29, 39 and panels 32 and 44) it is believed one description is sufficient, using panel 25 of section *a* as the example, and showing the related elements of section *b* in parentheses.

At the score lines 29*a* (39*a*) at one end of each of the panels 25 (35) there are connected thereto supplemental end panels 29 (39) which are substantially the full length of the end of the box. To a longitudinal edge of the panels 29 (39) there are connected spacer panels 30 (40) by fold score lines 30*a* (40*a*). The opposite longitudinal edges of the spacer panels have connected thereto inert supplemental end panels 31 (41), as by fold score lines 31*a* (41*a*).

At the opposite ends of the respective panels 25 (35), there are connected semi or substantially half-length sup-

plemental panels 32 (44), as at fold score lines 32a (44a); and to a longitudinal edge of panels 32 (44) there is connected semi or half-length spacer panels 33 (43) at fold score lines 33a (43a). At the opposite longitudinal edges of the respective spacer panels 33 (43) there are connected semi or half-length inner supplemental panels 34 (42) by fold score lines 34a (42a).

Following the foregoing manner of describing the relatively opposite panel sections, the panel sections c and d are likewise similar except for diagonal transposition of panels 48 and 53. Using a similar system of description and using section c as the basis for description, there are outer end panels 45 (50), connected to the respective opposite end edges of bottom panel 22, at fold score lines 45a (50a), and at the opposite edges of the respective panels 45 (50) there are connected spacer panels 46 (51) at fold score lines 46a (51a). At the respective opposite edges of the spacer panels 46 (51) there are connected inner end panels 47 (52), as at fold score lines 47a (52a), and at one end of each of the inner end panels 47 (52) there are connected supplemental sidewall wing panels 48 (53), by fold score lines 48a (53a).

It will be noted that the end panels 29, 32, 39, 44, 45 and 50 each has an elongated slot 60 centrally thereof, which, when the box is formed, overlie in register in respective panels at opposite ends of the box to provide a hand-grip at each end of the box. Each of the end panels 31, 34, 41, 42, 47 and 52 may, if desired, have ventilating orifices or openings 61 therethrough, and since, when the box is formed, these panels overlie the plane of the panels having the hand-grip slots, and are spaced therefrom by the spacer panels 30, 33, 40, 43, 46 and 51 there is provided a chamber in the end walls having ventilating openings for the interior of the box, or Dry Ice refrigerant may be received in said space. The panels 31, 41, 47 and 52 may be provided with an extended locking tongue 62, at the outer longitudinal edge thereof for releasably entering the slots 23 when the box is formed, and the cover closure flaps 26 and 36 may have indentations 28 and 38 in the free longitudinal edges for convenience in lifting said cover closure flaps, regardless of whether said flaps be severed from the box on the tear lines 27, 37.

In bending the several panels of the blank into box forming relation, as best shown in Figs. 2 and 3; the units of panels in sections a and b are folded upwardly on scored lines 25a and 35a whereupon the semi or half panels 34 and 42 are folded inward and downward on the score lines 34a and 42a and again folded on score lines 33a and 43a to overlie the respective half panels 32, 44, whereby the spacer panels 33 and 43 maintain a space between said overlying half panels. The half panel units are then folded inwardly on score lines 32a and 44a at a right angle so that they are substantially aligned over score lines 45a and 50a, and thus become sections of the opposite end walls of the box. This upward folding of sections a and b also raises the panels 25 and 35 vertically to become the opposite outer side walls of the box, with the cover flap panels 26, 36 connected thereto at the respective fold lines 26a and 36a.

The next successive operation is to fold the units of panels 29, 30, 31 and 39, 40, 41 inwardly at a right angle on the respective score lines 29a and 39a, and bend the panels 31 and 41 down into the box on the respective score lines 30a and 40a and again on score lines 31a and 41a, the spacer panels 30 and 40 overlying the previously folded spacer panels 33 and 43, the panels 39 and 41 overlying the previously folded half panels 42 and 44, and the panels 29 and 31 overlying the previously folded half panels 32 and 34 at opposite ends of the box.

The next operation is to fold upwardly the units of the panel sections c and d on score lines 45a and 50a, whereby the end panel units 45, 46, 47 and 50, 51, 52 including wing panels 48 and 53 stand vertical at the opposite ends of the box, whereupon the panels 47 and

52 may be folded down into the box on the respective score lines 46a, 47a and 51a, 52a, whereby the panels 45, 47 and 50, 52 overlie each opposite face of the previously folded end panels, the spacer panels 46 and 51 overlying the previously folded spacer panels, whereupon the locking tongues 62 on the opposite end panels 31, 47 and 41, 52 may be locked into the slots 23, the end panels 47 and 52 thus becoming the inner end panels within the folded box.

In the operation of folding the panel sections c and d, the wing panels 48 and 53 which are connected to inner end panels 47, 52, at score lines 48a and 53a, respectively, are folded backwardly as shown by broken lines in Fig. 3, whereby, when panels 48 and 53 are initially folded into the box they would overlie the face of end panels 47 and 52. However, the wing panels 48 and 53 are in reality supplemental sidewall panels and, when within the formed box, they may then, respectively, be folded on score lines 48a and 53a, to parallelly overlie the opposite sidewall panels 25 and 35, in superficial contact therewith, their height being sufficiently less than the height of said sidewall panels so that the upper edge of said supplemental sidewall panels 48, 53, substantially register parallel with the tear lines 27 and 37 of the closure flaps. Thus, when the cover flaps are torn free on said tear lines, an open and free sight-display may be made of the top layer of contents and including a portion of the side view of the upper layer of the contents of the box. The length of said supplemental sidewall panels 48, 53 is preferably the same as the length of the inner exposed face of the side walls, which manifestly is the total inner longitudinal dimension of the side walls minus the thickness of the end walls as defined by the combined width of the spacer panels 46 and 51 of the inner end panels which are the last of the end panels folded into the box; wherefore, these supplemental sidewall wing panels 48, 53 extend from end to end of the inner exposed face dimension of the side walls of the box and provide a double thickness of sidewalls for strength, and also provide a brace to hold the relatively opposed inner end panels 47, 52 in place.

When the body of the box is so formed rectangularly, as shown in Fig. 5, it is obvious that the cover closure flaps 26, 36 may be bent on score lines 26a, 36a to a closing position as shown in Fig. 4. When it is desired to open the box it is manifest that the closure cover flaps 26 and 36 may be readily lifted as shown in Fig. 5, either with or without the use of finger-grip insets 28, 38, and if desired, may be removed by severance on tear lines 27, 37.

From the foregoing description in connection with the drawings, it will be seen that a box has been formed which effectively utilizes all material in a substantially rectangular blank and in which there are six panels of overlying material for vertical support in each end wall of the box, each of said composite end walls consisting of three layers of panels in overlying superficial contact constituting an outer section of end walls and three layers in overlying superficial contact constituting an inner section of end walls, said outer and inner sections being overlying and relatively spaced by the spacer panels, the outer section preferably having registered hand grip openings 60 therethrough, and the inner section preferably having registered ventilating orifices 61 therethrough, the box having a double wall at its sides, and having top cover flaps or panels which may be removed on a tear line which is spaced in a side wall below the top of the box, whereby when the top is torn on said tear line, the upper contents of the box may be opened to sight and display from the top and side of the box, the upper edges of the supplemental side wall panels being in parallel register with the tear lines.

Having thus described the invention, what is claimed as new and patentable is:

1. A packing box of foldable material comprising a

plurality of integral panels relatively foldable from a blank including a rectangular bottom panel having lock slots adjacent opposite ends, relatively opposite side walls having one edge connected to the bottom panel and having top closure panels connected to the opposite edge, and relatively opposite end panels having a plurality of layers of pairs of end panels the planes of which overlie relatively, said end wall panels having spacer panels between pairs thereof whereby said end wall panels are in spaced relation providing a chamber therebetween, one of said end wall panels being an inner panel at each end of the box and having a locking tongue engageable in said lock slots of the bottom panel, a pair of supplemental side wing panels each having one end foldably connected by score lines to an end of one of said inner end wall panels, said supplemental side wing panels being of a length adapted for folding on such score lines to extend the entire length of the exposed face of the side wall of the box between the relatively opposed faces of the end walls of the box, said top closure panels being connected to the side wall panels along a weakened tear line in the side wall panel of the box adjacently spaced from the score line of the top panels, and said supplemental side wall panels being of a height substantially equal to the height of the side wall panels below the weakened tear line.

2. A foldable integral blank for folding into box-forming relation comprising, in a flat plane, a generally rectangular blank including a rectangular bottom panel having score-line connection thereto at each peripheral side thereof of a foldable section of panels, said foldable sections each including side wall panels and end wall panels relatively scored and slotted for forming into box-forming relation, the end wall panels in each of said sections having therebetween elongated relatively narrow spacer panels whereby the end wall panels in that section may be relatively folded to overlie in spaced

10
15

25

relation when the blank is folded into box-forming relation and provide end walls at each end of the box having a chamber within relatively spaced end wall panels, two of said sections in said blank being relatively opposite and each including a side wall panel and a top closure panel, a pair of supplemental side wall wing panels each having one of its ends connected at a score line to one end of an inner end panel, said supplemental wing panels each being foldable on said score line perpendicular to its connected inner end panel, the said wing panels having a length which, when added to the combined width of the two spacer panels of the two inner end wall panels, is substantially equal to the length of the side wall panels, whereby said supplemental wing panels may be folded to overlie substantially the entire length of the inner exposed face of the side walls between said inner end panels in the folded box, said side wall panels respectively having a weakened tear line adjacently spaced from the fold score line of the top panel, and the supplemental side wall wing panels being of a transverse width substantially similar to the transverse width of the side wall panels between said weakened tear line and the opposite edge of the side wall panel which is connected to the bottom panel.
